UNITED STATES PATENT OFFICE.

ALFRED INGRAM AND HARRY INGRAM, OF BROOKLYN, NEW YORK, ASSIGNEES TO INGRAMS INCORPORATED, OF BROOKLYN, NEW YORK, A CORPORATION OF NEW YORK.

CLOSURE FOR TUMBLERS, JARS, BOTTLES, AND OTHER RECEPTACLES.

1,353,398.

Specification of Letters Patent. Patented Sept. 21, 1920.

Application filed August 10, 1916, Serial No. 114,091. Renewed January 27, 1920. Serial No. 354,514.

To all whom it may concern:

Be it known that we, ALFRED INGRAM and HARRY INGRAM, citizens of the United States, and residents of Brooklyn, in the 5 county of Kings and State of New York, have invented certain new and useful Improvements in or Relating to Closures for Tumblers, Jars, Bottles, and other Receptacles, of which the following is a specification.

The invention pertains more particularly to the art of hermetically sealing tumblers, jars, bottles and other receptacles by means of applied caps and gaskets held in sealing 15 position by atmospheric pressure or by what is commonly known as the vacuum sealing process.

The invention involves a novel construction and combination of cap and gasket 20 with the receptacle, and also a cap of a flexible material, exemplified by pyroxylin, as sheet celluloid, the use of which involves new methods of sealing and the attainment of new and highly beneficial results.

25 The difficulties incident to the effectual sealing by atmospheric pressure of tumblers, jars and the like are too well understood to require specific mention.

The purpose of our invention is to remedy 30 the objections existing to the closures as heretofore constructed and to provide a closure whose seal may be easily maintained by ordinary atmospheric pressure. A further purpose of the invention is to provide a 35 closure whose gasket is exterior to the upper rim portion of the receptacle and not exposed to contact with the contents of the receptacle. Our invention also provides a cap which will not contaminate the contents 40 of the vessel and will be capable of resisting saline products and also the acids commonly found in food products, such as in tomatoes, pickles, vinegar and the like, so that the cap itself shall not be detrimental to the contents 45 of the receptacle, but in every way cleanly, non-corrosive and wholesome.

The cap of our invention is also one which may with its inclosed gasket be so deformed 50 preferably, but not necessarily, by atmospheric pressure alone as to constitute an efficient seal, and conform to any irregularities, wave lines and the like which may exist along the rim of the receptacle, the cap

itself by its engagement with said rim preferably affording a sealing zone and excluding the contents of the receptacle from contact with the gasket. The cap may be readily removed from the receptacle, since in its preferable form it is of thin light material capable of being easily punctured thus 60 destroying the vacuum within the receptacle and loosening the cap. By our invention we are enabled to dispense entirely with the use of sheet metal as a closure though some of the features of our invention may be employed in connection with such closures.

In carrying out our invention we preferably make the cap of odorless pyroxylin material known as "celluloid," and, by preference, the sheets of this material from 70 which we produce the caps are from about five to twenty-five one-thousandths of an inch in thickness, according to the diameter of the cap, and are transparent, so that the top of the contents of the receptacle may be 75 inspected without breaking the seal. The preferred form of cap is one represented by a flat disk having a depending skirt portion whose lower part is set inwardly so as to pass in reasonably close relation to the side 80 of the receptacle when the cap is placed thereon. We prefer to make the upper portion of the cap of greater diameter than the mouth of the receptacle so as to form a recess or groove to hold the gasket, which gasket preferably sets laterally outwardly from the top of the rim of the receptacle and permits the bottom surface of the cap to directly engage the top of said rim. When the cap thus constructed is pressed with reasonable firmness upon the receptacle, then, after the exhausting operation has been performed, or the heated contents of the receptacle have cooled, atmospheric pressure, assisted by mechanical means, if desired, will 90 dish the top of the cap downwardly and thus cause the edge portions of the cap to be pulled inwardly whereby the skirt portion of the cap squeezes the gasket against the sides of the receptacle adjacent to the rim 95 thereof. The air pressure also maintains the material of the top of the cap closely against the rim of the receptacle, and the sealing becomes not only highly efficient but permanent.

The invention will be fully understood

from the detailed description hereinafter presented, reference being had to the accompanying drawings, in which:

Figure 1 is a side elevation, partly in section, illustrating a receptacle with the cap of our invention applied thereto, the parts being shown in their initial relation or prior to the sealing of the receptacle;

Fig. 2 is a corresponding view illustrating the relation of the parts after the receptacle has been sealed and the seal maintained by pneumatic pressure; and

Fig. 3 is a sectional view, partly broken away, showing somewhat diagrammatically a vacuum chamber and one means for effecting the sealing of a receptacle in accordance with our invention.

In the drawings, referring to Figs. 1, 2 and 3, the numeral 1 designates a tumbler, 20 2 the contents thereof, and 3 a cap or closure for said tumbler.

The cap is in one integral piece and of disk outline, and has a depending annular flange or skirt portion which, when the cap is to be applied to a receptacle having straight as distinguished from offset outer side walls, is preferably composed of an upper part 4 and a lower part 5, the part 4 being offset from the part 5 and, with the 25 outer lower edge portions of the top of the cap, forming an annular groove 6, within which is placed a sealing ring or gasket 7. The gasket is yielding and preferably of rubberlike material in the shape of a flat 35 vertical band. At its upper edge it is against the lower surface of the inner outer portion of the top of the cap and at its lower portion said gasket rests upon the shoulder afforded by the offset between the 40 portions 4 and 5 of the cap.

The cap or closure 3 and gasket 7 are, in Figs. 1 and 3, shown in their initial condition and as placed freely upon the tumbler or other receptacle 1. The cap or closure 45 will be manufactured with regard to the diameter of the top of the receptacle so that when placed thereon it may, with reasonable snugness, fit over the mouth of the same.

The sealing of the receptacle is preferably effected by atmospheric pressure alone and the sealing operation results (though it may be assisted by other means, as hereinafter set forth) in the cap or closure and gasket being transformed from the condition in 55 which they are represented in Figs. 1 and 3 to that illustrated in Fig. 2, in which it will be seen that the top of the cap or closure is dished downwardly within the upper portion of the receptacle and that the outer 60 edge portions of the cap or closure have been drawn inwardly against the gasket and also preferably downwardly against the upper edge of the receptacle. The downward dishing of the top of the cap and the 65 drawing inwardly of the upper outer edge

portions of the cap result in the gasket being compressed against the side of the receptacle, the inner face of the gasket conforming to the side of the receptacle.

The hermetic sealing of the receptacle 70 with the use of our invention may be performed in various ways and in many well-known forms of apparatus commonly designated as vacuum sealing machines and also as jar sealing apparatus, and in Fig. 3 we 75 illustrate somewhat diagrammatically a sufficient portion of one form of vacuum sealing apparatus suitable for practising our invention, although without any intention of limiting the invention to the use of apparatus 80 nor to the use of the apparatus shown.

In Fig. 3, 8 designates the outer wall or casing of a vacuum chamber, 9 the top cap of the chamber, 10 the bottom cap thereof, 11 a valved pipe leading to suitable air exhausting apparatus, not shown, 12 a valved pipe for admitting air at the proper time to the vacuum chamber, 13 a vertically movable perforated platen within the vacuum chamber, 14 an operating rod connected with 90 said platen, 15 a cylinder or tube through which said rod has its movement, and 16 a cup-piston on said rod engaging the inner walls of said cylinder or tube 15.

In effecting the sealing, the tumbler or other receptacle 1 will have the cap or closure 3 placed thereon and introduced into the vacuum chamber, and this may be done by first lifting the cap 9 from off the chamber. The rod 14 and platen 13 will be positioned above the receptacle 1 and cap or closure 3, with sufficient space between the platen and cap or closure to permit the latter to rise, during the exhausting operation, without entirely losing its connection with 105 the receptacle. After the receptacle, cap or closure and platen have been positioned, the pipe 12 will be closed, as shown, and the pipe 11 will be opened so that the air-exhausting apparatus, not shown, may become effective to exhaust the air from the 110 vacuum chamber, including the air contained within the receptacle 1 and its contents, all this being according to well-known methods; and thereupon the platen 13 will 115 be depressed so as to move the cap or closure downwardly and firmly upon the upper edge of the receptacle, and thereafter the valve in the pipe 11 will be turned to cut off the air exhausting apparatus from the vacuum 120 chamber and the valve in the pipe 12 opened to admit atmospheric air to said chamber, with the result that there being a vacuum in the receptacle 1, the air pressure will act against the cap or closure 3 to transform 125 said cap or closure and the gasket 7 from their condition shown in Fig. 1 to that illustrated in Fig. 2 and hereinbefore described.

The caps or closures hereinbefore described are made from circular disks pref- 130

erably cut from sheets of the material of which the caps are to be made, and when the caps or closures are to be produced in the outline shown in our illustration that is, 5 having an offset portion to provide a groove for the gasket or packing ring, care must be taken in the transformation of the disks into the caps so that the material may not be torn or injured by the machine or machinery 10 employed.

In the closures herein described, there is a sealing zone effected by the gasket, although a further effective sealing is preferably caused to take place by the contact of 15 the material of the cap itself with the upper edge or rim of the receptacle, the effectiveness of this further sealing being due to the nature and yielding character of the material of which the cap is preferably formed, 20 it possessing characteristics which adapt it, during the sealing operation, to closely hug the edge of the mouth of the receptacle even to the extent of yielding to the inequalities that may exist in said edge. Pyroxylin ma- 25 terial possesses special characteristics adapting it, as we have discovered, to the hermetic sealing of receptacles by air pressure. We preferably use transparent celluloid for the caps so that the interior of the receptacle 30 may be easily inspected through the cap, and we preferably make use of very thin sheet celluloid in the production of the caps since we have found that thin celluloid sheets of from five to ten one-thousandths of an inch 35 in thickness afford better results than could be attained by an unduly thick sheet of celluloid such as might be used for the lid of a box.

Pyroxylin material is known by many 40 names, but we recommend the use of what is commonly known as "odorless celluloid" for the production of the caps, this being a pyroxylin material devoid of the commonly-known odor of camphor which is one of the 45 ingredients sometimes employed in the manufacture of the material.

We have hereinbefore described our invention in its applicability to cold vacuum sealing processes, but we would have it 50 understood that our invention may also be utilized in the sealing of receptacles by the so-called heat vacuum process. No apparatus of any kind is necessarily used in the sealing operation for, in many instances, the 55 cooling of the hot contents of the receptacle will reduce the pressure within the receptacle sufficiently to enable the preponderance of atmospheric pressure outside to maintain an effective seal and the distortion of the cap 60 in the sealing operation may be produced by such preponderance of pressure alone, or by mechanical means alone, or by the two together.

Also, while we have illustrated and de- 65 scribed our invention as applied to the seal-

ing of a tumbler and have described the dishing of the cap as being caused by atmospheric pressure alone, the invention is, obviously, not limited in those respects. Any kind or form of receptacle may be used and, 70 when the receptacle has a projecting flange or a groove near its upper edge, the skirt of the cap may be made straight instead of being offset as illustrated, the gasket, in that case, being held between the cap and the 75 groove or flange in the receptacle. Also it is obvious that mechanical pressure may be employed to assist the air pressure in dishing the cap while being applied to the receptacle. 80

What we claim as our invention and desire to secure by Letters Patent, is:

1. The combination with a receptacle within which the air pressure has been reduced, of a hermetic closure maintained 85 thereon by atmospheric pressure, comprising a cap seated upon the rim of the receptacle and having a downwardly extending flange or skirt the lower portion of which bears against the side of the receptacle, and a 90 gasket around the upper outer side portion of the receptacle above the lower portion of the flange and extending to said rim between said side portion and said flange, the upper portion of the flange and the top of the cap 95 being of yieldable material, said cap by reason of the atmospheric pressure thereon closely binding against said rim and binding said gasket against the receptacle at and below said rim. 100

2. The combination with a receptacle within which the air pressure has been reduced, of a hermetic closure maintained thereon by atmospheric pressure, comprising a cap seated upon the rim of the receptacle and having a flange or skirt, the upper portion of the flange and the top of the cap being of yieldable material and the lower portion of the flange bearing against the side of the receptacle, and a gasket 110 around the upper outer side portion of the receptacle and extending to said rim between said side portion and said flange, said cap by reason of the atmospheric pressure thereon closely binding against said rim and binding said gasket against the receptacle at and below said rim, and said cap in the upper portion of its flange having an annular recess exterior to said rim within which a portion of the gasket is held compressed. 115

3. The combination with a receptacle within which the air pressure has been reduced, of a hermetic closure maintained thereon by atmospheric pressure, comprising a cap having a depending annular flange extending downwardly upon the side of the receptacle, the flange and top of the cap being of yieldable material, and a gasket extending around the inner upper portion of said flange exterior to the rim of the recep- 125 130

tacle, said cap in its upper portion being in a materially contracted state, as distinguished from its initial diameter when placed on the receptacle, and firmly binding the gasket in a deformed condition against the upper outer side edges of the receptacle.

4. The combination with a receptacle within which the air pressure has been reduced, of a hermetic closure maintained thereon by atmospheric pressure, comprising a cap of celluloid or like material having a depending annular flange extending downwardly upon the side of the receptacle, and a gasket extending around the inner upper portion of said flange exterior to the rim of the receptacle, said cap in its upper portion being in a materially contracted state, due to the atmospheric pressure and the nature of its material, as distinguished from its initial diameter when placed on the receptacle, and firmly binding the gasket in a deformed condition against the upper outer side edges of the receptacle.

5. The combination with a receptacle within which the air pressure has been reduced, of a hermetic closure maintained thereon by atmospheric pressure, comprising a cap of celluloid or like material seated on the rim of the receptacle and having a depending annular flange, contractible by depression of the top portion of the cap, and a sealing gasket between the wall of the receptacle and the flange above the lower portion of the flange.

35 6. As a new article of manufacture, a receptacle within which the air pressure has been reduced, and a hermetic closure maintained thereon by atmospheric pressure comprising an annularly contracted cap of celluloid or like material seated on the rim of the receptacle and having a depending annular flange, and a sealing gasket against which said cap is contracted with sealing effect by contraction of the flange below the 45 gasket against the wall of the receptacle

upon depression of the top portion of the cap.

7. As a new article of manufacture, a receptacle within which the air pressure has been reduced, and a hermetic closure maintained thereon by atmospheric pressure, said closure comprising a cap having a top portion seated on the rim of the receptacle and a depending annular flange formed of yieldable material and at its lower portion bearing against the wall of the receptacle, and a gasket fitted between the flange and wall of the receptacle, the flange being contractible by depression of the top of the cap to grip the gasket and wall of the receptacle with sealing effect.

8. A receptacle closure having a central portion and a depending flange, the flange and top of the closure being of yieldable material, said flange being adapted to embrace a gasket about and exterior to the mouth of the receptacle and to contract about such gasket when said central portion is subjected to atmospheric pressure due to a lowered pressure within the jar.

9. The combination of a receptacle, a gasket adapted to fit about the neck of said receptacle exterior thereto and at the rim thereof and a closure having a central portion and a flange, the central portion and flange being of yieldable material, said flange being adapted to embrace said gasket about the neck of said receptacle and to contract about said gasket to seal the receptacle when the central portion of the closure is depressed.

Signed at New York city, in the county of New York and State of New York, this 7th day of August, A. D. 1916.
